UNITED STATES PATENT OFFICE.

ALBERT ROZIER, OF WEMBLEY, ENGLAND.

ELECTRIC ELEVATOR.

1,141,979.

Specification of Letters Patent.

Patented June 8, 1915.

Application filed June 14, 1912. Serial No. 703,615.

To all whom it may concern:

Be it known that I, ALBERT ROZIER, a subject of the King of Great Britain and Ireland, residing at 2 Clayton avenue, Wembley, in the county of Middlesex, England, have invented a new and useful Improvement in Electric Elevators, of which the following is a specification.

My invention relates to electrically controlled lifts or elevators, and has for its object to provide means, automatically operated by the closing of the gate thereof or its equivalent to cause movement of the lift or elevator in the desired direction, thus obviating the necessity of the liftman closing the gate or its equivalent and then moving a controller to operate the lift as is the practice at present.

The invention is particularly adapted for use with lifts or elevators of the kind operated by electric motors between two floors only as in underground railways, though it is of course applicable to other types of electrically controlled lifts in which the elevating power is not necessarily electricity.

To this end according to the present invention, electric switch mechanism automatically operated by the closing of the gate or its equivalent is employed, said switch mechanism when thus operated performing the functions usually performed by the hand controller operated by the liftman, to control the various movements of the lift. A suitable selecting mechanism adapted to be set by the liftman may be placed upon the gate or its equivalent, or elsewhere in the lift to actuate the switch mechanism when the gate is closed.

To enable the invention to be fully understood it will now be described by reference to the accompanying drawings in which—

Figure 1 is an end view showing two sets of contacts attached to a portion of the frame of the lift above the gate, and also a portion of the lift gate having selective contact actuating means arranged according to one form of the invention; Fig. 2 is a front view of the same; Fig. 3 is a diagrammatic view showing by way of example a set of gate operated contacts connected up to elevator control circuits such as are described in the specification of prior British Letters Patent No. 20950 of 1905, for "Improvements in controlling devices for electric mo-

tors applicable to the motors of elevators or lifts and the like."

Referring first to Figs. 1 and 2: Above the lift gate 1, are arranged two sets of contacts 2, 3, each consisting of four contact springs 4 connected to terminals 5 and mounted upon a suitable insulating block 6. One set of these contacts is adapted when operated to cause and control the upward movement of the lift, the other set the downward movement. The sets of four contacts 2, 3 are adapted to be bridged respectively by contact plates 7, 8, carried upon insulating blocks 9, 10, mounted on levers 11, 12 hinged at one end as shown. Mounted on the gate 1 is a two armed bent lever 13 pivoted at its center to a bracket 14 carried on the gate. The end *a* of this lever carries a pin 15 engaging in a slot 16 in a slide 17 adapted to be moved up or down by means of a handle 18. The slide 17 is guided in its movement by means of a bar 19 moving in a socket 20 on the gate. A spring pin 21 is arranged within the handle 18 and engages holes 22 in the door to lock the slide 17 in the desired position. In the position shown in the drawings the end *b* of the lever 13, as the gate is closed engages the underside of the lever 11 and raises the same, causing the contact plate 7, to bridge the contacts in set 2. When the slide 17 is moved up the door, the end *b* of the lever 13 is lowered out of action and the end *a* is raised into position to cause the corresponding lever 12 to bridge the contacts in set 3 when the gate is next closed. The slide 17, if desired may be placed in a middle or intermediate position in which case the lever 13 has no action upon either set of contacts when the gate is closed.

Fig. 3 shows the manner of connecting up the two sets of gate contacts 2, 3, hereinbefore described, to the elevator control circuits, fully described in the specification of prior British Letters Patent No. 20950 of 1905, to which reference may be had. The sets of contacts 2, 3, are merely substituted for the contacts upon switch 117 controlled by the hand lever 65 shown in said prior specification. The contacts 2, as here shown serve to connect up the limit switches 111, 112, 113, which may be placed in the elevator shaft and operated by a cam on the elevator car, or by the usual stop motion switch 109 suitably geared to the winding machinery so

as to operate the limit switches 111, 112, and 113 in successive order, in the well known manner, said limit switches controlling the upward movement of the elevator; the gate 5 operated lever for bridging the contacts 2 is indicated at 11. The contacts 3, serve to connect up similar cam operated limit switches 131, 132, 133, controlling the downward movement of the elevator, the gate operated lever for bridging said contacts 3 being indicated at 12.

The usual switch operated by the opening of the exit gate to break the control circuit is shown at 32 (Fig. 3). It will be obvious 15 that the present invention provides a more certain method of breaking the control circuit when the gate is opened, since the circuits controlled by both sets of contacts 2, 3 are broken as long as the gate remains open.

20 If desired, by regulating the length of the contact springs 4, the order of closing of the various circuits may be regulated. In the example shown, since the sets of contacts 2, 3, are made practically simultaneously, 25 the elevator will start at once on its full speed, which is the most desirable arrangement.

Obviously gate controlled switch mechanism according to this invention may be 30 adapted to suit any particular control system, the number and construction of the contacts, and the contact selecting means being varied as desired.

Having now particularly described and 35 ascertained the nature of my invention, and in what manner the same is to be performed, what I claim and desire to have protected by Letters Patent of the United States is:—

1. In an electrically controlled elevator, 40 the combination of an elevator gate, switch mechanism adjacent the path of movement of said gate for controlling the operation of the elevator, and manually controlled selective means arranged to operate said switch mechanism upon the closing of the gate.

2. In an electrically controlled elevator, 45 the combination of a switch for effecting an upward movement of the elevator, an additional switch for effecting a downward movement of the elevator, a gate, and selective means on the gate operative upon closing said gate for effecting the operation of either of said switches at will.

3. In an electrically controlled elevator, 55 the combination of a switch for effecting an upward movement of the elevator, an additional switch for effecting a downward movement of the elevator, a gate, and selective mechanism on the gate movable into position to effect the operation of either of said switches upon the closing of said gate.

4. In an electrically controlled elevator, 65 the combination of a switch for effecting an upward movement of the elevator, an additional switch for effecting a downward movement of the elevator, a gate, a device movable with the gate and co-acting with either of said switches upon closing the gate, and selective means for operating said device.

5. In an electrically controlled elevator, 70 the combination of a switch for effecting an upward movement of the elevator, an additional switch for effecting a downward movement of the elevator, a gate, a device 75 movable with the gate and co-acting with either of said switches upon closing the gate, selective means for operating said device, and means for locking said selective means in the desired position.

6. In an electrically controlled elevator, 80 the combination of a switch for effecting an upward movement of the car, an additional switch for effecting a downward movement of the car, a gate and a member carried by 85 the gate and arranged manually to be moved into operative relation with each of said switches whereby either one of the switches will be operated by the movement of the gate.

7. In an electrically controlled elevator, 90 the combination with the elevator controlling circuit, of a switch in said circuit arranged to effect an upward movement of the car, an additional switch in said circuit arranged to effect a downward movement of the car, a member pivoted to the car gate and arranged to be rotated into operative relation with each of said switches whereby one of said switches will be operated by closing the gate, manual means for rotating said member into a selective position, and a locking device for said manual means.

8. In an electrically controlled elevator, 95 the combination with a controlling circuit 100 for the car, of a car gate, a switch in said circuit for effecting an upward movement of the car, an additional switch in said circuit for effecting a downward movement of the car, a member pivoted to the car gate, 110 manual means for moving said member from a neutral position into a position of operative relation with either one of said switches, and means for locking said pivoted member in any one of its three positions.

In testimony whereof, I have signed my name to this specification in the presence of two subscribing witnesses.

ALBERT ROZIER.
